H. A. DOUGLAS,
CIRCUIT CONNECTOR.
APPLICATION FILED APR. 17, 1916.

1,236,553.

Patented Aug. 14, 1917.

Inventor
Harry A. Douglas
By G. L. Craigatty

UNITED STATES PATENT OFFICE.

HARRY A. DOUGLAS, OF BRONSON, MICHIGAN, ASSIGNOR TO DOUGLAS & RUDD MFG. CO., OF BRONSON, MICHIGAN, A CORPORATION OF MICHIGAN.

CIRCUIT-CONNECTOR.

1,236,553.

Specification of Letters Patent. Patented Aug. 14, 1917.

Application filed April 17, 1916. Serial No. 91,549.

To all whom it may concern:

Be it known that I, HARRY A. DOUGLAS, citizen of the United States, residing at Bronson, in the county of Branch and State of Michigan, have invented a certain new and useful Improvement in Circuit-Connectors, of which the following is a full, clear, concise, and exact description, reference being had to the accompanying drawings, forming a part of this specification.

My invention relates to connectors employing shells adapted for coupling engagement with contact carriers at their ends and which shells inclose contacts intervening between the aforesaid contact carriers, the invention having for its object an improved inter-relation of these intervening contacts with the end contacts and an improvement in the construction of the intermediate contact carriers to improve the facility for the assembly thereof with the contacts carried thereby.

My invention in one of its characteristics is a connector including a shell, outer contact carriers in the ends of the shell, one of these carriers being adjustable to different positions with respect to the shell to open and close circuit, an inner contact carrier within the shell and between the aforesaid contact carriers, a pair of contacts carried by the inner contact carrier and which are engageable with each other and separable respectively to close and open circuit, one of these contacts being engageable with a contact upon the adjustable outer contact carrier and the other of these contacts being engageable with a contact upon the other of the outer contact carriers, said adjustable outer contact carrier, in both of its positions, limiting the outward movement of the adjacent contact upon the inner contact carrier, and a spring for separating the contacts carried by the inner contact carrier when said adjustable outer contact carrier is in circuit opening position and to the extent permitted by this contact carrier and permitting said adjustable outer contact carrier to effect engagement between the contacts carried by the inner carrier when this outer contact carrier is in its circuit closing position.

The carrier of my invention includes a carrying portion having an opening therein, a contact projecting from said carrier

through said opening, and spring means for 55 thrusting said contact outwardly, the carrier and contact having interengagement to limit the extent to which the contact may be outwardly thrust, said carrier being formed in sections in adjacent portions of which adjacent parts of said opening are formed to permit the contact to be laid in position.

Furthermore my invention includes the provision of a contact carrier formed in sections having interfitting portions, the sections being movable into and out of assembled relation by direct bodily movement toward and away from each other, said interfitting portions serving to hold the sections against relative movement in predetermined 70 directions when assembled. In addition the shell containing the contact carrier is so constructed as to positively maintain the sections of the carrier in place when said sections are assembled in the shell.

I will explain my invention more fully by reference to the accompanying drawing showing two embodiments thereof and in which Figure 1 is a view in elevation, partially in section, of a connector made in accordance with the invention; Fig. 2 shows parts appearing in Fig. 1 some being in different adjustment; Fig. 3 is a perspective view of a component part; Fig. 4 illustrates a detail of construction; Fig. 5 is a view on line 5 5 of Fig. 1; Fig. 6 is a view of another embodiment of the invention, partially in elevation and partially in section; Fig. 7 illustrates a detail of construction, an inclosing shell being shown in section; and Fig. 8 is a view on line 8 8 of Fig. 6.

Like parts are indicated by similar characters of reference throughout the different figures.

Referring first to the form of the invention shown in Figs. 1 to 5 inclusive, there is there shown a metallic shell 1 inclosing a contact carrier 2 of insulating material, this contact carrier being centrally disposed when the shell is employed and constructed 95 to couple the lamp 3 and a plug 4 or other outer contact carriers, though the invention is not to be limited to this form of connector. When constructed for this purpose the shell desirably has bayonet slots at each end, the 100 bayonet slots 5 at one end being adapted to receive bayonet pins 6 upon the contact carrier portion or base of the lamp, the lamp

desirably having only one relative position with respect to the shell when the lamp and the shell are coupled. These bayonet slots and pins constitute coupling formations.

5 The bayonet slots at the other end of the shell are provided with two seats 7 and 8 (constituting coupling formations) that are separated longitudinally of the shell whereby the bayonet pins 9 (also constituting coupling formations) may be interengaged with the shell at different places longitudinally thereof for the purpose of holding the plug 4 in assembly with the shell while the plug is either in its inner or outer position, the arrangement being such that when the plug is in its innermost position it will be included in circuit and when it is in its outer position it will be excluded from circuit. While the plug illustrated merely serves as a

10 contact terminal carrier for the conducting wires 10 and 11 leading thereto from a suitable source of current, the invention is not to be limited to a plug that is employed for this purpose. The form of the invention illustrated in Figs. 1 to 5 inclusive is a so-called single pole connector, the lamp 3 having a metallic sheath 12 connected with one terminal of the lamp filament 13 whose other terminal is connected with the central contact 16 upon the inner end of the lamp base. The lamp filament is included in circuit by way of the metallic shell 1 and the sheath 12 and also the metallic pins 6 connected with this sheath. The plug 4 also has a metallic

15 sheath 17 connected with the conductor 11, the conductor 10 being connected with the central contact 18 upon the inner end of the plug. The inner contact carrier 2 carries two spring pressed cylindrical or tubular

20 contacts 19 and 20, between which a coiled spring 21 is disposed to spread these contacts apart to maintain the contact 19 in engagement with the contact 16 and the contact 20 in engagement with the contact 18, the latter engagement being maintained whether the plug 4 is in its inner position (when the circuit is closed) or is in its outer position (when the circuit is opened). The spring 21 thus not only operates to

25 spread the contacts 19 and 20 apart to open the circuit when the contact carrier 4 is placed in its outer position but also exerts outward pressure upon the outer contact carriers. The contact 19 is extended longitudinally and is enlarged at its inner end where it is slotted as indicated at 22 to form contacting spring fingers 23. The inner end of the contact 20 is also desirably enlarged but is maintained sufficiently small to enable it

30 to enter the adjacent end of the contact 19 there to have engagement with the spring fingers 23, this result occurring when the bayonet pins 9 are in the inner seats 7. The opening through the inner contact carrier that receives the contacts 19 and 24 is

reduced at its outer ends whereby the extent to which the contacts 19 and 20 may be spread apart while within the carrier is limited. When these bayonet pins are in the outer seats 8 the spring 21 will eject the contact 20 from the bore of the tubular contact 19, this spring continuing to maintain engagement between the contacts 18 and 20 when the plug 4 is in its outer position to maintain the plug 4 and the shell 1 in mechanical assembly after the circuit is broken consequent upon the separation of the contacts 19 and 20. As the spring 21 is metallic it is provided with a cup-shaped seat 24 of insulation so that the spring cannot act as a conductor, a necessity when the plug is in its outermost position. The contact carrier is made up of two semi-circular blocks whose diametrical faces have interlocking engagement. The preferred form of interlocking engagement is procured by means of two radially directed semi-cylindrical beads 25 one projecting from the diametrical face of each semi-circular block and entering a similarly shaped recess in the diametrical face of the opposing block, these diametrical faces being disposed where the elements 19, 20 and 21 are located to permit of the ready assembly of these elements with their carrier.

The construction shown in Figs. 6, 7 and 8 has parts which are similar in function to parts of the structure shown in Figs. 1 to 5 inclusive. The parts of the structure shown in Figs. 6 to 8 inclusive which are generally similar in function to corresponding parts shown in Figs. 1 to 5 inclusive are given similar characters of reference with the addition of prime exponents. The connector shown in Figs. 6 to 8 inclusive is a so-called double pole connector and in such case the lamp base is provided with end contacts 26, 27 (constituting terminals of the filament 13¹) while the plug is provided with end contacts 28, 29 (constituting terminals of conductors 10¹, 11¹). The contacts 30 and 31 are adapted for engagement respectively with the contacts 26 and 27 while the contacts 32 and 33 are adapted for engagement respectively with the contacts 28 and 29. A spring 34 is interposed between the contacts 30 and 32 to maintain them respectively in engagement with the contacts 26 and 28 when the circuit is closed. A spring 35 is interposed between the contacts 31 and 33 to maintain them respectively in engagement with the contacts 27 and 29 when the circuit is closed. A flexible conductor 36 electrically connects the contacts 30 and 32 but I have shown the contacts 31 and 33 as being in telescopic engagement with each other whereby they are included in circuit. When the lamp is to be excluded from circuit the plug may be turned to bring the pins 9¹ in the seats 8¹ whereupon the springs 130

34 and 35 will press the contacts 32 and 33 upon the insulation surrounding the contacts 28 and 29. Instead of dividing the contact carrier 24 longitudinally of the shell 5 I divide it transversely of such shell into two disks. Each disk carries a radial projection 25¹ entering a correspondingly shaped recess in the other disk.

In both forms of construction illustrated in the drawings the interlocking formations 25, 25¹ serve to prevent displacement of component parts of the intermediate contact carriers and by forming these contact carriers in sections the assembly therewith of 15 the contacts carried thereby may very readily be effected, since the component parts of the inner carrier meet at the center of the contact receiving opening in the carrier whereby the contacts and their spreading 20 springs may readily be laid in the part or parts of the opening when such component parts are separated. The contact carriers are desirably rigidly secured within the shells either by tight driving fit or by means 25 of inturned ears such as indicated at 37 in Fig. 1.

While I have herein shown and particularly described two embodiments of my invention I do not wish to be limited to the 30 precise details of construction shown as changes may readily be made without departing from the spirit of my invention, but having thus described my invention I claim as new and desire to secure by Letters Patent the following:

1. A connector including a shell having bayonet slots in the ends thereof, the slot at one end having two bayonet pin receiving seats separated longitudinally of the shell; 40 outer contact carriers in the ends of the shell, these contact carriers having bayonet pins receivable in the adjacent bayonet slots in the shell, the outer contact carrier coupled with the end of the shell whose bayonet slot has two bayonet pin receiving seats being adjustable longitudinally of the shell into inner and outer positions for respectively closing and opening circuit; an inner 45 contact carrier within the shell and between the aforesaid contact carriers; a pair of contacts carried by the inner contact carrier and which are engageable with each other and separable respectively to close and open circuit, one of these contacts being engageable 50 with a contact upon the longitudinally adjustable outer contact carrier and the other of these contacts being engageable with a contact upon the other of the outer contact carriers, said longitudinally adjustable outer 55 contact carrier, in both of its positions, limiting the outward movement of the adjacent contact upon the inner contact carrier; and a spring for separating the contacts carried by the inner contact carrier when said longitudinally adjustable outer contact carrier is in

its outer position and to the extent permitted by this contact carrier, then to open circuit, and permitting said longitudinally adjustable outer contact carrier to effect engagement between the contacts carried by the inner carrier when this outer contact carrier is in its inner position, to close circuit.

2. A connector including a shell; outer contact carriers in the ends of the shell, one of these carriers being adjustable to different positions with respect to the shell to open and close circuit; an inner contact carrier within the shell and between the aforesaid contact carriers; a pair of contacts carried by the inner contact carrier and which are engageable with each other and separable respectively to close and open circuit, one of these contacts being engageable with a contact upon the adjustable outer contact carrier and the other of these contacts being engageable with a contact upon the other of the outer contact carriers, said adjustable outer contact carrier, in both of its positions, limiting the outward movement of the adjacent contact upon the inner contact carrier; and a spring for separating the contacts carried by the inner contact carrier when said adjustable outer contact carrier is in circuit opening position and to the extent permitted by this contact carrier, and permitting said adjustable outer contact carrier to effect engagement between the contacts carried by the inner carrier when this outer contact carrier is in its circuit closing position.

3. A contact carrier formed of sections and having an opening therethrough located partially in each section thereof, contacts in said opening movable into and out of engagement to close and open a circuit, and means constantly tending to move the contacts out of engagement.

4. A contact carrier formed of sections and having an opening therethrough located partially in each section thereof, contacts in said opening movable into and out of engagement to close and open a circuit, means constantly tending to move the contacts out of engagement, and means for limiting the circuit opening movements of the contacts.

5. A contact carrier comprising a pair of interfitting sections movable into and out of assembled relation by direct bodily movement toward and away from each other, a contact movably mounted in the carrier, and means constantly tending to thrust said contact outwardly.

6. A connector comprising a contact carrier formed of a pair of interfitting sections movable into and out of assembled relation by direct bodily movement toward and away from each other and having an opening therein located partially in each section, a contact movably mounted in the opening,

means constantly tending to thrust said contact outwardly, and a shell receiving the carrier sections and coacting therewith to positively hold said sections in assembled relation.

7. A connector comprising a contact carrier formed of a pair of interfitting sections movable into and out of assembled relation by direct bodily movement toward and away from each other and having an opening therein located partially in each section, a contact movably mounted in the opening and having interengagement with a section of the carrier to limit outward movement of the contact, means constantly tending to thrust said contact outwardly, and a shell receiving the carrier sections and coacting therewith to positively hold said sections in assembled relation.
- 10 8. A connector comprising a shell, a contact carrier within the shell formed of sections, means on the shell engaging the ends of the sections to hold the latter in assem-

bled relation within the shell, and a contact mounted in the carrier.

9. A connector comprising a shell, a contact carrier within the shell formed of sections having interfitting portions whereby said sections are held against relative movement in predetermined directions, means on the shell engaging the ends of the sections to hold the latter in assembled relation within the shell, and a contact mounted in the carrier.

10. A connector comprising a shell, a contact carrier within the shell formed of sections, tongues struck from the shell and engaging the ends of the sections to hold the latter in assembled relation within the shell, and a contact mounted in the carrier.

In witness whereof I hereunto subscribe my name this 7th day of April, A. D. 1916.

HARRY A. DOUGLAS.
